SOFA

Adrian M. Pearsall, Forty Fort, Pa., assignor to Craft Associates, Inc., Wilkes-Barre, Pa., a corporation of Pennsylvania

Filed Mar. 5, 1965, Ser. No. 84,118

Term of patent 14 years

(Cl. D15—11)

FIG. 1 is a front elevational view of a sofa showing my design;

FIG. 2 is a front perspective view thereof with the cushions removed for convenience of illustration;

FIG. 3 is a plan view of the sofa of FIG. 2;

FIG. 4 is a rear elevational view; and

FIG. 5 is an end elevational view, the undisclosed end being a mirror image thereof.

The dominant features of my design reside in those portions shown in full lines.

I claim:

The ornamental design for a sofa, as shown and described.
